COMPOSITION FLOOR COVERING OR THE LIKE

Thomas P. Hayes, Arlington, Mass., assignor to Boston Woven Hose and Rubber Company, Cambridge, Mass., a corporation of Massachusetts

Application January 12, 1955, Serial No. 33,938

Term of patent 14 years

(Cl. D92—4)

Fig. 1

Fig. 1 is a plan view of a composition floor covering or the like, showing my new design. The dot and dash lines on the figure outline a design unit which is repeated in regular succession as indicated by extensions beyond the unit boundaries.

Fig. 2 is a view on an enlarged scale showing a portion of the design.

I claim:

The ornamental design for a composition floor covering or the like, substantially as shown and described.
